UNITED STATES PATENT OFFICE.

THEODORE C. SALVETER, OF ST. CHARLES, MISSOURI, ASSIGNOR OF ONE-HALF OF HIS RIGHT TO ROBERT H. PARKS, OF SAME PLACE.

RAILWAY DRAW-BAR.

SPECIFICATION forming part of Letters Patent No. 224,358, dated February 10, 1880.

Application filed October 20, 1879.

To all whom it may concern:

Be it known that I, THEODORE C. SALVETER, of St. Charles, Missouri, have made a new and useful Improvement in Railway-Cars, of which 5 the following is a full, clear, and exact description, reference being had to the annexed drawings, making part of this specification, in which—

Figure 1 is a central longitudinal section 10 taken through a car having the improvement; Fig. 2, a plan of the end of the car, the flooring being removed; Fig. 3, a cross-section taken on the line *x x* of Fig. 2; Fig. 4, a longitudinal section taken through a draw-head; 15 Fig. 5, cross-sections taken on the lines *x* and *y* of Fig. 4; Fig. 6, a plan of a draw-head; Fig. 7, views of the block used for filling the space in the draw-head above the draft-rod; Fig. 8, views of the key used in locking the draft-rod 20 in the draw-head; Fig. 9, views of the sleeve which is around the draft-rod within the spring; and Fig. 10, views of the swivel used to connect the portions of the draft-rod, being, respectively, a horizontal and a vertical section. 25 The same letters denote the same parts.

This invention has relation to the draw-heads of the car, their construction, and mode of uniting them.

Referring to the drawings, A represents a 30 car having the improvement, and which, saving as modified by the improvement, may be of the usual form and construction, and which, also, may be either a freight or passenger car.

B B' represent the draw-heads. C C' C² represent the draft-rod, it being made in sections, the parts C C' connecting, respectively, with the draw-heads B B', and the parts C C' C² being connected together by means of the swivels D D. The latter are elongated, as shown 40 in Figs. 1, 2, 10, partly to enable the sections C C' to be moved freely inward from the ends of the car without compressing the central portion of the rod, and partly to provide for clearing the king-bolts E E, which are arranged in 45 their usual places, passing from the floor of the car down through the transoms F F and swivels D D, as shown in Fig. 1, the swivels being wide enough to admit the bolts and long enough to provide ample space between the 50 bolts and the heads c c' of the sections C C' for

the latter to move in without coming in contact with the bolts.

The rod is connected with the draw-heads as follows: The parts C C' are provided with heads c² c², and the draw-heads are slotted at 55 *b*, the shape of the slot corresponding to that of the rod, as shown in Figs. 4, 5, 6. The rods are dropped into the slots, and there fastened by means of a key, b', which is passed through the draw-head above the rods, as in Figs. 4 60 and 6, and secured in place by a pin, b². The advantage of this connection is, that with a given size of draw-head the union is a stronger one than when, as is customary, the draft-rod is flattened at the end and is held in the draw-head by means of a pin passing through the draw-head and through a perforation in the flattened end of the rod. The usual spring G is interposed between the draw-head and chafing-plate H. A sleeve, I, made in two parts, 65 i i, encircles the rod within the spring, and serves to keep the latter centrally in place. A filling-block, K, may be used to fill the space in the slot *b* above the rod.

In the present improvement the draft-timbers L L extend from one chafing-plate, H, to the other chafing-plate, H', and are brought much nearer each other, a space of two inches apart being the preferred practice. This provides room for the draft-rod, and also brings 80 the timbers substantially in line with and between the draw-heads.

The advantages of this construction are, that crushing strains, as well as pulling strains, are much better sustained. It also provides 85 for readily inspecting and reaching the draw-heads, as the timbers do not, as hitherto has been the practice, extend out alongside the draw-heads. A continuous draft-timber also materially aids in strengthening and stiffening 90 the car and in increasing its carrying capacity.

The draft-timbers may be bolted to the sills a a, or they may, as shown, be made in one piece with the sills, and, saving when they are intended to sustain an inward thrust upon 95 the draw-heads, they may be spaced farther apart than as shown.

I claim—

1. The combination of the draw-heads B B', sections C C' C², and swivels D D, said sections 100

slipping in said swivels and said swivels receiving the king-bolts, substantially as described.

2. The combination, in a car, of the rods C 5 C², swivel D, and bolt E, said rods slipping in said swivel and said bolt passing through the swivel, substantially as described.

3. The combination of the rods C C², swivel 10 D, bolt E, and transom F, said rods slipping in and said bolt passing through said swivel, substantially as described.

4. The combination of the draw-head B, having the slot b, key b', and the rod C, having the head c², said slot being shaped to receive the head of the rod, substantially as described. 15
Witness my hand this 6th October, 1879.

T. C. SALVETER.
